UNITED STATES PATENT OFFICE.

JOHN ENGLEHEART, OF WAUCONDA, WASHINGTON.

STIRRUP ATTACHMENT.

No. 802,274.

Specification of Letters Patent.

Patented Oct. 17, 1905.

Application filed May 24, 1904. Serial No. 209,476.

To all whom it may concern:

Be it known that I, JOHN ENGLEHEART, a citizen of the United States, residing at Wauconda, in the county of Okanogan and State 5 of Washington, have invented new and useful Improvements in Stirrup Attachments, of which the following is a specification.

This invention relates to a strap or belt fastener, and forms a simple, cheap, and ready 10 means for uniting two or more straps placed flatwise against each other, holding them securely and preventing their separation when subjected to longitudinal tension.

A further advantage of my invention re- 15 sides in the ready and simple means for disconnecting the straps or belts without the use of tools of any description, the hands alone being sufficient for the purpose.

In the accompanying drawings, Figures 1 20 and 2 represent opposite sides of two straps or belts connected by my improved fastening device. Fig. 3 is a sectional view on the line *aa* of Fig. 1. Fig. 4 is a cross-sectional view on the line *bb* of Fig. 2. Fig. 5 is a perspective view of the fastening device disconnected from the straps.

Similar numerals refer to the same parts in 25 all the figures.

1 and 2 indicate two straps or belts placed 30 flatwise against each other and connected by two fastening devices. The strap 1 in this case has two longitudinal rows of equally-spaced perforations 4, those of one row being transversely disposed with relation to those 35 of the other row. Similar perforations 5 are formed in the strap 2, which perforations when placed over those in the strap 1 are co-incident therewith.

In making the fastener 3 I take a piece of 40 wire of suitable length and bend the same to form a cross-bar 6, which is bent at right angles at its ends to construct arms 7. I then bend the ends of the arms downwardly in vertical position to form a pair of legs 8, which 45 are spaced apart at suitable distance, as shown. By thus bending the wire to construct the legs the arms 7 will be at right angles with said legs. On the upper ends of the legs I form spurs or projections 9, the same 50 being constructed by means of flattening the upper surfaces of said arms and cross-bar. By means of the projections 9 I am enabled to do away with bending the wire to form the projection-spurs. Further, my construction 55 of projections is in direct contact with the intersections of the arms and legs and arranged

on the upper portions of said legs, so as to be flush with one of the straps when attached thereto.

To use my fastening device, the straps to be 60 joined are placed together and the perforations alined. The legs 8 are then passed through two of the perforations 4 and 5 in each strap and turned down to bring the body portions 7 within the perforations. This 65 movement will cause the flattened sides of the cross-bar 6 and legs 8 to bear snugly against the sides of the straps on opposite sides. The spurs 9, which are also brought outside the perforations, project in opposite 70 direction to the legs 8 and bear against the strap above the perforations, (see Fig. 3,) locking the straps securely together without danger of separation when the straps are pulled in opposite directions. In fact, the 75 greater the tension on the straps the more securely will the fastener hold. The straps are quickly separated by grasping the upper end of strap 1 and pulling it outwardly. This 80 will cause the spurs to slip through the perforations therein and raise the legs 8, which will then in turn pass through the perforations. The number of fastening devices necessary to unite two or more straps or belts 85 will depend upon the use to which said straps or belts are put. Two fasteners are shown in the drawings, this number being considered necessary in the great majority of cases. When used with wide straps, it would be advantageous to use two or more fasteners in 90 transverse as well as in longitudinal relation.

It will be observed that the flattened sides of the legs 8 engage the surface of the strap throughout their length and are parallel to the flattened face of the head 6, and as the 95 body portions 7 are perpendicular to the flattened sides of the legs and the head the pull of the strap on the body portions will have no tendency whatever to disengage the legs from the strap nor to force their ends into 100 the strap. Consequently the strap will not be injured by the ends of the legs, nor is there any danger of moving the legs to disengage the spur 9 so long as the strain is in line with both straps. It will also be observed 105 that the spurs 9 project beyond the body portions in the same plane as the legs and have a positive bearing on the strap.

Having thus described the invention, what is claimed as new is—

A device for securing a plurality of perforated straps facewise together, comprising

a fastener made from a suitable length of wire, said wire being bent to form a transverse cross-bar having arms bent from their opposite ends at right angles therewith, the 5 arms being bent at their terminals to construct legs arranged at right angles with the arms and said arms and cross-bar being flattened to form upwardly-projecting single spurs in direct contact with the intersections

of the legs and arms, said spurs being arranged to extend above the arms and cross-bar, substantially as specified.

In testimony whereof I affix my signature in presence of two witnesses.

JOHN ENGLEHEART.
